HUGH B. PITCHER, OF BOONTON, NEW JERSEY, ASSIGNOR TO CURTAINLESS SHOWER COMPANY, OF NEW YORK, N. Y., A CORPORATION OF DELAWARE.

CLOSURE FOR SHOWER-BATH ATTACHMENTS.

1,316,739.

Specification of Letters Patent. Patented Sept. 23, 1919.

Application filed May 12, 1917. Serial No. 168,095.

To all whom it may concern:

Be it known that I, HUGH B. PITCHER, a citizen of the United States, and resident of Boonton, in the county of Morris and State 5 of New Jersey, have invented certain new and useful Improvement in Closures for Shower-Bath Attachments, of which the following is a specification.

In certain types of demountable shower 10 bath attachments, such as is shown in the patent to Kenney, Reissue No. 13,911, dated May 4, 1915, it is usual to provide a base adapted to be attached to the water supplying faucets of the bath tub and to provide 15 two openings or outlets from such a base. One of these openings is designed to open upwardly into a supply pipe leading to the spray heads and the other is designed to open downwardly into the bath tub, to form in 20 effect a continuation of the usual faucet outlet. The latter opening is usually provided with some closure means so arranged that when actively disposed the water from the faucet is directed through the supply pipe 25 to the spray-heads and when removed the water is permitted to flow directly into the tub. The present forms of these closures, possess numerous defects, the most serious of 30 which is that either they permit a leakage when in closing position or else are so complicated that it requires a prolonged manipulation to move them to or from a closing position.

Accordingly, the primary object of my invention is to provide an improved form of 35 closure which can be quickly moved to and from an operative or closing position and which when actively disposed will securely seal the opening leading into the tub.

40 A further object of the invention is to organize the closure in connection with tension means acting on the same, that the closure is automatically moved into a position clear of the stream through the outlet opening 45 when the closure is shifted manually into a position offset from the opening.

Another defect inherent in known shower 50 bath attachment bases of the class described is that, when the depending outlet is open, the water is frequently forced up the supply pipe resulting in a spraying discharge from the spray heads or at least there is caused an objectionable dripping of water from the spray heads.

55 Accordingly, another object of the inven-

tion is to provide a form of base in which all the water from the faucet is caused to flow down through the open outlet without backing up through the spray head supply pipe.

Various other objects and advantages of 60 the invention will be in part obvious from an inspection of the accompanying drawings and in part will be more fully set forth in the following particular description of one form of mechanism embodying my invention, and the invention also consists in 65 certain new and novel features of construction and combination of parts hereinafter set forth and claimed.

In the drawings: 70
Figure 1 is a view in side elevation of a lower portion of a shower bath attachment connected to a water faucet and showing a preferred embodiment of my invention with the closure in position to close the depend- 75 ing outlet.

Fig. 2 is a vertical sectional view through the device shown in Fig. 1, and with the closure actively disposed; and

Fig. 3 is a view similar to Fig. 2, showing 80 the closure in an inoperative position.

In the following description and in the claims, parts will be identified by specific names for convenience of expression but they are intended to be as generic in their 85 application to similar parts as the art will permit.

In the drawings, there is shown a conventional form of water faucet 4 to which is attached the lower portion of a shower 90 bath attachment of the type described. The attachment includes a supporting base portion 5 supported from the faucet or other convenient support by means of the U-fastening loops 6. The base is in the form of a 95 horizontally disposed casting projecting forwardly from the faucet and provided with a Z-shaped water passageway 7. One upturned end 8 of the passageway is in fluid communication with the faucet 4 and the 100 other end 9 of which is downwardly curved and enters into the wide bore 10 of the integral depending pipe 11 constituting the discharged outlet nozzle into the tub. The upper portion of the base is provided with a bore 12 opening down into the bore 10. The lower end of an upstanding pipe 13 which leads to the spray heads (not shown) is threaded into the upper end of the bore 12.

This construction differs from the conven- 110

tional form, in that a slightly curved tongue 14 depends into the bore 10 from the upper side of the casting and is arranged so as to curve the liquid passing through the passageway 7 downwardly through the outlet at the bottom of the casting. This tongue is so spaced from the opposite wall outlining the bore 10 that a choked by-pass 15 is formed which is so arranged that when the discharge through the pipe 11 is intercepted the water will pass about the lower edge of the tongue and up into the pipe 13.

The closure herein illustrated may be regarded as a separate article of manufacture and is arranged to be installed, not only upon the particular form of shower bath base herein illustrated, but with obvious mechanical changes may be designed to be installed on any bath device of this general character now in use.

The closure includes a stamped metal cap 16 outlined by an upturned flange rim 17, the inner side of which is cut away as shown at 18 to facilitate the movement of the cap to and from its closing position, as shown respectively in Figs. 2 and 3. A packing of some compressible material 19 is fitted within the cap and arranged to engage the end of the pipe 11 when the closure is actively disposed as shown in Fig. 2. A spring stop 20 in the form of a flanged cap is slidably mounted upon the pipe 13 and has opposite sides pivotally connected to opposite sides of the flanged rim 17 by means of a pair of rods 21. This stop constitutes a bearing for the upper end of a coiled spring 22 which is guided on the pipe 13 and in turn bears upon the upper face of the base which is flattened to provide a seat 23 for the lower end of the spring.

Assuming that the closure is in its operative position as shown in Fig. 1 and that it is desired to open the flow through the pipe 11 into the bath tub, the closure is simply swung laterally of the pipe 11 in the direction indicated by the arrow in Fig. 1. The reduced portion 18 of the flange permits the packing 19 to be slipped away from the pipe end without damage to the packing and without any particular resistance from the spring 22. When the closure is drawn clear or partly clear of the pipe 11, the pulling tension thereon is released which permits the spring 22 to act on the stop 20 and thus draw the closure into the raised tilted position shown in Fig. 3. While in this position it will be noted that the closure is off-set from and entirely clear of any stream issuing through the pipe 11, so that there is avoided the flapping effect characterizing the swinging types of closures now used in devices of this character.

When in open position the flow through the passageway 7 is directed downwardly through the discharge opening and in this

construction there is eliminated the objectionable back filling of the upstanding pipe 13 which has heretofore resulted from high pressure through the faucet supplying such devices now in general use.

70

Should it be desired to close the outlet, the cap is grasped and drawn down thus compressing the spring and the cap is slipped in under the pipe end. Releasing the hold on the cap permits the spring to firmly draw the cap into closing engagement with the outlet as shown in Fig. 2.

75

The closing member and its coacting springs and parts may be readily installed in position on the conventional forms of shower bath bases simply by separating the supply pipe from the base portion and threading the stop and spring in order on the pipe after which the pipe is re-rotated into threaded engagement with the base.

80

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

90

Having thus described my invention, I claim:

95

1. In a shower bath attachment, a base therefore comprising a casting provided with means for mounting the same in position on a bath tub faucet, said casting provided with a water conducting passageway including a horizontally disposed portion with an inlet at one end adapted to receive water from the supporting faucet and a depending outlet at the opposite end, said outlet being relatively large in cross-section compared with the cross-section of the horizontally disposed portion of the passageway, a second outlet above said depending outlet, a curved tongue depending from the top of the casting toward said outlet to curve the flow from said horizontal portion into said depending outlet, the lower end of said tongue being spaced from said depending outlet to form a passageway leading to said second outlet and means for intercepting the flow through said depending outlet thereby to cause the flow to pass about the lower end of said tongue and out through the second outlet.

100

2. In a shower bath attachment, a member provided with a water conducting passageway having a horizontal portion and a depending outlet at one end, a curved tongue depending into said passageway toward said outlet thereby to curve the flow from said horizontal portion into said depending outlet when the said outlet is open, said tongue spaced from the adjacent wall of the passageway to form an upwardly directing outlet and means for closing said outlet.

105

110

115

120

125

130

depending outlet thereby to cause the water to flow about said tongue and out through said upwardly directing outlet.

3. In a shower bath attachment, a casting in the form of a T provided with a water conducting passageway including a horizontal portion with an upwardly extending opening and a downwardly extending opening therefrom, an upstanding supply pipe demountably screwed into said upwardly extending opening, a stop cap slidably mounted on said pipe, a spring guided on said pipe and positioned between the casting and cap, a closure for the downwardly extending outlet and means connecting said stop cap and closure, said spring adapted to act on said closure when in inoperative position to draw the same into position clear of the liquid stream discharged from said downwardly extending outlet.

4. In a shower bath attachment, a base provided with a depending outlet pipe, an upstanding supply pipe positioned above said outlet, a stop member slidably mounted on said pipe and free to move upwardly

thereon, a compression spring disposed between the stop and base, a closure for the outlet, and a link connection between the closure and said stop, said spring adapted to act on said closure for holding the same in operative position and to expand its full distance to hold the closure in an inoperative position.

5. In a device of the class described, a conduit provided with an outlet on one side and a spring guiding member positioned on the opposite side, a cap slidably mounted on said guiding member, a spring coiled about said guiding member between said conduit and said cap and adapted to bear on the cap to force the same in a direction away from the conduit, a closure for said outlet, and a rod connecting said closure with said cap whereby the spring will act through the sliding cap and rod to hold the closure in position.

Signed at New York city in the county of New York and State of New York this 7th day of May A. D. 1917.

HUGH B. PITCHER.
